UNITED STATES PATENT OFFICE.

SIMON W. WARDWELL, OF PROVIDENCE, RHODE ISLAND.

DETECTOR DEVICE.

No. 849,296.

Specification of Letters Patent.

Patented April 2, 1907.

Application filed January 24, 1906. Serial No. 297,692.

To all whom it may concern:

Be it known that I, SIMON W. WARDWELL, a citizen of the United States, residing at Providence, in the county of Providence and 5 State of Rhode Island, have invented certain new and useful Improvements in Detector Devices, of which the following is a specification.

My invention is a device for detecting defective insulation, particularly in the winding processes of preparing and making electrical coils for electromagnets, electrical instruments, and similar purposes where perfect insulation is essential.

15 In the accompanying drawings, which form a part of this specification, Figure 1 represents my invention as applied to a winding device, showing how it is used; Fig. 2, a detail of the invention, being sectional of Fig. 3 20 on the line A A; Fig. 3, a detail in elevation; Fig. 4, a section on the line 2 2 of Fig. 2.

Fig. 1 shows the device partly in diagram to illustrate the electrical connections. In it 2 represents the shaft or spindle of a 25 winding-machine, and 3 a supply from which the insulated wire is unwound.

4 is a guide-wheel over which the insulated wire is drawn in its course from the supply 3 to the spindle 2, on which it is wound. Connected with the winding-spindle 2 is a stop device of usual form, such as is employed to arrest the machine's operation upon the occurrence of a defect, the breaking of the material wound, or the exhaustion of the supply. 35 Herein is shown and described only those elements or adjustments of the stop device which directly act to effect the stopping of the winding when there occurs a defect in or lack of insulation on the wire being wound. 40 The spindle 2 and its adjuncts, the device for holding the supply 3, and the guide-wheel 4, together with the stop devices referred to, are all components of the winding-machine.

On the spindle of the winding-machine or 45 connected with it is a toothed wheel or ratchet 5.

Adjacent the ratchet is fulcrumed a lever 6, in which is slidably mounted a bar or dagger 7, whose extremity 8 normally lies close to 50 but out of the path of action of the ratchet 5, retained there by any suitable agency, as the weight of the lever 6.

Closely adjacent to the lever 6 is an electric motor—for instance, an electromagnet 9— 55 and said magnet is part of an electrical cir-

cuit which derives its current from a suitable source of electrical energy 10. The circuit extends from the source 10 aforesaid to the machine, preferably to the metal spindle or core 11, which holds the supply 3, and thence 60 to the wire 12, one end of which is electrically connected with the machine. This cannot well be shown in the drawings; but an obvious mode of connection is to wrap the loose end from the inside of the supply-coil 3 about 65 the supply-spindle 11. The other side of the electrical circuit runs to the electromagnet 9, including it, and extending therefrom to the guide-wheel 4, to which it is electrically connected, as shown in Fig. 1, by attachment to 70 the pin or stud 14, on which the wheel turns, or, in Fig. 2, by a brush 13, which bears on the hub of the guide-wheel.

When connected as shown in Fig. 2, the guide-wheel is electrically insulated from the 75 rest of the machine and its connections by suitable means.

As indicated in Fig. 3, the stud 14 is supported in a bushing 15, of insulating material, and its head 16 and the nut 17 are likewise insulated by the washers 18 and 19 from adjacent metal. The circuit thus formed is manifestly an open circuit, energized on the + side as far as the guide-wheel 4 and on the - side to the insulated wire 12, which 85 runs over the wheel. Were there no insulation whatever on the wire, or were the wire bare in spots or so loosely insulated as to metallically contact with the wheel 4, then the circuit would be closed and the magnet 9 90 would be energized, the lever 6 would be drawn toward the magnet, and the dagger 7 would be moved into the path of action of the ratchet 5 and by it shifted, and the movement of the dagger would act upon or affect 95 the stop devices of the machine to arrest its action.

The stopping mechanism of the machine may be of any well-known arrangement, one means for controlling it being illustrated in 100 Fig. 1, in which a lever 23 is mounted on a rocket-shaft 24, adapted to throw the clutch or other device. At its lower end the lever 23 has a shoulder 25, engaging a corresponding shoulder on the detent-lever 26. The 105 detent-lever 26 is connected by a wire 27 to a rocking member 28, pivoted on the stud 29 and engaged by a pin 30, projecting from the dagger 7. When the dagger 7 is engaged and moved by the ratchet 5, the mem- 110

ber 28 is rocked or tilted, and the wire 27 lifts the detent-lever 26, releasing the lever 23, and allowing the shaft 24 to rock, under action of a spring 31, to act on the clutch 5 mechanism to stop the machine; but sometimes the insulation, though defective for use in an electrical coil, is so little impaired that in passing over the guide-wheel 4 the wire will not metallically touch said wheel 10 and effect electrical contact therewith. It is therefore necessary to provide means which, without injuring the perfect insulation, shall penetrate insulation that is loose or otherwise defective. This is accomplished by 15 providing a series of small flexible feelers or contacts, as the coils of the spring 20, which is an endless ring of helically-coiled polished wire that encompasses and lies within the groove 21 of the guide-wheel 4. The insulated wire is led upon the guide-wheel to one side of the spring 20, passes under it, and to the other side of the spring, as indicated in Fig. 3. As the wheel-groove 21 and the wire of the spring are polished and as the tension 25 of the spring is light, the insulation suffers no injury as the wire is drawn past the spring; but the coils of the spring lie at such an angle and its tension is sufficiently great that when the insulation has been abraded or is unduly 30 loose one or more of the springs' coils penetrates to the metal of the wire and the electrical circuit is closed between the wire 12 and the wheel 4 through the spring 20.

The action of the spring-ring 20 is practically that of a feeler, kneading and feeling the wire all over as it passes to the winding and through the instrumentalities described arresting the winding when any insufficiency is felt.

40 Without limiting myself to any precise arrangement or mode of application, I claim—

1. In a detecting device for insulated wire the combination with a grooved wheel over which the wire runs, of a helical spring surrounding the wheel within its groove, for the purpose specified.

2. In a detecting device for insulated wire or cable, the combination of a wheel or pulley over which the wire is led, and an endless 50 helical spring surrounding the periphery of the wheel and adapted to bear on the wire.

3. The combination with the stopping devices of a machine for winding insulated wire, and a supply from which the wire is wound 55 and a guide-wheel over which the wire travels, of electrical means to actuate the stopping devices of the machine, an electrical circuit including, with a source of electrical energy, the said electrical means, the wire 60 being wound and the guide-wheel, and means to electrically connect said wire with said guide-wheel, in the manner and for the purpose indicated.

4. The combination with an electromagnetic stop device, of an electric circuit, a

traveling wire forming one terminal of the circuit, a guide-wheel for the wire forming the other terminal, and means to electrically connect the wire with the wheel.

5. The combination in a normally open 70 electrical circuit with an electromagnetic stop device, of a traveling insulated wire forming one terminal of the circuit, a guide-wheel for the wire forming the other terminal of the circuit, and means to electrically connect the wire with the wheel. 75

6. The combination in a normally open electrical circuit with an electromagnetic stop device, of a traveling insulated wire 80 forming one terminal of the circuit, a guide-wheel for the wire forming the other terminal of the circuit, and a ring of coiled spring-wire surrounding the periphery of the guide-wheel and contacting with the insulated wire to electrically connect the wire with the wheel. 85

7. The combination in a normally open electrical circuit with an electromagnetic stop device, of a traveling insulated wire forming one terminal of the circuit, a grooved guide-wheel forming the other terminal of 90 the circuit, and a ring of coiled spring-wire within the groove of the wheel, for the purpose specified.

8. The combination with a winding-machine having as components a winding-spindle 95 2, devices for holding the supply 3 and a guide-wheel 4, electrically insulated from the machine, of an insulated wire wound from said supply upon the spindle 2, and passing over the wheel 4, an electrical circuit having 100 one terminal in the machine and another in said wire, stop devices included in the electrical circuit, and means carried on the guide-wheel 4 to connect the terminals, when a defect occurs in the insulation of said wire. 105

9. The combination with means for feeding an insulated strip, of a stop device therefor, an electrical motor and generator for operating said device, and a contact member arranged in circuit including said motor, generator and part of the strip said contact member comprising a wheel or pulley over which the strip is traveled and a spring feeler-band surrounding the periphery of said wheel and bearing on the strip. 110 115

10. The combination with a traveling covered strip and means for feeding the same, of an electric generator connected electrically with the strip and idler-pulley or guide-wheel over which said strip travels, a member carried by said guide-wheel and arranged to contact with said strip and with any part thereof where the core is exposed, a stop device for the feeding means, and an electric motor to operate the same in circuit with the 120 generator, the contact member and strip. 125

11. The combination with means for delivering a metallic coated strip from its supply and with a stop device and electric motor therefor, of a feeler member having flexible 130

contact-fingers arranged to contact with said strip, and a circuit including a generator, said member, the motor and the strip.

12. In a machine for winding a covered metallic strip, the combination of the winding devices, a supply from which the strip is drawn, a stop device, means for electrically operating the same on completing a circuit through the strip, and a member arranged in the circuit to complete the circuit when the metallic part of the strip is in contact with said member, said member formed with flexible teeth or projections for kneading and feeling the covering of the strip.

15 13. In a detecting device for machines for

winding insulated metallic strips, the combination with a normally open electrical circuit including the strip, of a feeling device also included in the circuit comprising a plurality of yielding fingers adapted to be pressed into contact with the strip to close the circuit when defective insulation occurs.

In testimony whereof I have signed my name to this specification in the presence of two subscribing witnesses.
